CONVERTIBLE SETTEE-BED

James E. Plew, Valparaiso, Fla.

Application October 26, 1936, Serial No. 107,686

3 Claims.

(Cl. 5—43)

This invention relates to convertible furniture in general; and more particularly to a chair or settee which can be converted readily into a bed.

The main object of the invention is to provide an attractive piece of furniture which normally has all the appearance of an upholstered settee; and which can be converted to a bed by a slight change in position of the settee as a whole.

A further object of the invention is to provide an upholstered piece of furniture of the character described, in which the settee upholstery may be used to reinforce and form a species of box spring for the mattress with which the device is provided.

Another object of the invention is to provide a device of this character in which the several parts are so positioned with respect to each other as to constitute a counterbalanced piece of furniture which can be moved from one position to another with very little effort on the part of the user.

Other objects of the invention will become apparent as the detailed description thereof proceeds.

In the drawing:

Figure 1 is a perspective view of the convertible bed-settee;

Figure 2 is a vertical transverse section taken on a section line adjacent to one of the ends of the device;

Figure 3 is a vertical transverse section illustrating the parts of the device moved to a position different from that shown in Figure 2;

Figure 4 is a fragmentary longitudinal section taken on the line 4—4 of Figure 3;

Figure 5 is a fragmentary detail of a locking mechanism forming part of this invention; and

Figure 6 is a fragmentary detail of a bolt forming one of the elements of the invention.

As shown in the drawing, the device comprises a framework designated generally by the reference numeral 1. This framework which may be constructed of any suitable material, includes the ends 8 and 9 connected at their rear edges by runners 10 and 11. The rear wall of the settee is formed by a woven bed spring 12 suitably secured at its opposite edges to the runners 10 and 11 and at its opposite ends to the end walls 8 and 9.

The runners 10 and 11 are channel shaped in cross-section, and with the spring 12 form a chamber adapted to receive the mattress 13. The flanges 14 and 15 of the channel runners serve to hold the mattress 13 in position against the spring 12. Flaps 16 and 17 are hinged to the

outer extensions 18 and 19 of the end walls 8 and 9, by means of hinges 20 and 21, respectively, which are so designed as to permit the flaps 16 and 17 to fold inwardly against the mattress 13 to hold the ends thereof in position against the spring 12.

Hinges 20 and 21 prevent the flaps 16 and 17 from moving outwardly with respect to the mattress 13 beyond the planes of the outer faces of the end walls 8 and 9. In order to hold these flaps 16 and 17 in their open positions as shown in Figure 4 of the drawing, these flaps are provided with turn buttons 22 and 23 pivoted above their hinge axes.

When the buttons 22 and 23 are in the position shown in Figure 3, it is obvious that they will prevent any inward folding of the flaps about their hinge axes. When the flaps are folded down, as shown in Figure 2, the turn buttons 22 and 23 may be rotated to engage the flanges 15 in order to lock the said flaps in such folded position.

Each of the turn buttons 22 and 23 is rotatably mounted on its flap by means of a pivot 25 which extends through the flap, and is provided on such extension with a knob 26 by means of which the buttons can be readily turned from the outer faces of the flaps.

The back 27 of the settee is formed by a cushion, the back of which rests against the bed spring 12. The ends of the cushion are suitably secured to the end walls 8 and 9 of the framework. This cushion 27 forms in effect, an additional supporting means or box spring for the bed spring 12.

The seat of the settee is formed by a cushion 28 extending between the inner faces of the end walls 8 and 9. Slats 29 and 30 are fixed to the inner faces of the end walls 8 and 9 in proper position to form supports for the ends of the cushion 28, when the latter is located in position to form a seat.

Pivot pins 31 and 32 extend from the end walls 8 and 9, respectively, through bearing apertures formed in brackets 33 and 34 suitably secured to the lower face of the cushion 28. This pivotal connection between cushion 28 and the end walls 8 and 9 is located so that when the cushion 28 is rotated about the pivot axis, it will lie in contact with the back cushion 27.

The opposite ends of the cushion 28 are provided with spring bolts 35 (see Figure 6), adapted to seat alternatively in apertures 36 and 37 formed in the inner faces of the end walls 8 and 9. The bolt receiving apertures 36 are so located as to lock the cushion 28 in its seating position shown in Figure 2; while the bolt receiving apertures 37

are so located as to permit the cushion 28 to be rotated to its position shown in Figure 4.

As shown in Figure 4, the cushion 28 is rotated so that its outer faces are in contact with the outer faces of the end walls 8 and 9, and the slats 29 and 30 are in proper position to support the ends of the cushion 28.

When the cushion 28 is in this position, the bolt receiving apertures 36 are located so as to lock the cushion 28 in its seating position shown in Figure 2; while the bolt receiving apertures 37

are so located as to permit the cushion 28 to be rotated to its position shown in Figure 4.

As shown in Figure 5, the bolt 35 is provided with a head 38 and a shank 39 which is received in the bolt receiving aperture 36. The shank 39 is provided with a shoulder 40 which is received in the bolt receiving aperture 37.

The bolt 35 is provided with a head 38 and a shank 39 which is received in the bolt receiving aperture 36. The shank 39 is provided with a shoulder 40 which is received in the bolt receiving aperture 37.

The bolt 35 is provided with a head 38 and a shank 39 which is received in the bolt receiving aperture 36. The shank 39 is provided with a shoulder 40 which is received in the bolt receiving aperture 37.

The bolt 35 is provided with a head 38 and a shank 39 which is received in the bolt receiving aperture 36. The shank 39 is provided with a shoulder 40 which is received in the bolt receiving aperture 37.

The bolt 35 is provided with a head 38 and a shank 39 which is received in the bolt receiving aperture 36. The shank 39 is provided with a shoulder 40 which is received in the bolt receiving aperture 37.

are located in position to hold the cushion 28 in contact with the back cushion 27.

Each bolt 35 is mounted to slide in an L-shaped bracket 38 secured to the bottom face of the cushion 28 near the opposite ends thereof. A compression spring 39 is arranged between the bracket 38 and a washer or shoulder 40 formed on, or suitably secured to the bolt 25, the arrangement being such that the bolts 35 are pressed normally against the inner faces of the end walls 8 and 9, so that the bolts snap normally into their apertures when moved into position coincident therewith.

As shown in the drawing, the end walls 8 and 9 have their lower outer corners cut away on arcs of circles, in order to adapt the device to be readily rolled from the settee position shown in Figure 2, to the bed position shown in Figure 3. The center 41 from which the circular ends are struck is located so that the device is substantially balanced in all positions intermediate those shown in Figures 2 and 3 of the drawing.

In order to hold the device in either of its alternative positions, the end walls 8 and 9 are provided with rods 42 and 43, respectively. The rod 42 is mounted to slide radially with respect to the arcuate end of the wall 8 through a bracket 43' which is suitably secured to the outer face of the end wall 8. A pin 44 projects from the bracket 43' and is adapted to be engaged by a hook 45 formed on one arm of the lever which is pivoted between its ends on a pin 46 suitably secured to and projecting from the rod 42. A spring 47 suitably secured to the bracket 43 normally engages the hook 45 when located over the pin 44, in order to hold the said hook in locking position. A handle 48 forming part of the locking lever just described, may be used to move the hook 45 into and out of locking position relative to the pin 44.

The pins 44 and 46 are so located that when the hook portion 45 is in locking position on the pin 44, the lower beveled edge 49 of the rod 42 lies in the same plane as the lower edge of the end wall 8. The rod 42 is also beveled to form an edge 50 lying in the same plane as the front edge of the wall 8 when the rod 42 is in its extended and locked position. When it is desired to convert the device from a settee to a bed, the rod 42 must be withdrawn radially through the bracket 43 to permit the proper rolling of the end walls 8 from the position shown in Figure 2 to the position indicated in Figure 3. The rod 42 may then be moved into locked position to hold the device in its new position. The rod 43 is mounted on the outer face of the end wall 9 in exactly the same manner as the rod 42 is mounted on the end wall 8. The description of the rod 42 and the means for connecting it to the end

wall 8, therefore apply in every respect to the rod 43.

It will be obvious from inspection of the drawing, that the balanced construction of the framework and the arrangement of the various parts thereon, enable the device to be converted from one use to another with very little effort on the part of the user. It will also be obvious from inspection of Figure 3 of the drawing that the seat cushion 28 in its new position forms a substantial yielding reinforcement for the back cushion 27 in supporting the spring 12 and the mattress placed thereon. In other words, the cushions 27 and 28 constitute a very efficient box spring for the bed spring 12.

It is to be understood that the invention is not to be considered as limited to the specific construction and arrangement described herein, since it is evident that many changes may be made without departing from the scope of the invention as defined by the claims appended hereto.

What I claim is:

1. A convertible bed seat comprising a pair of vertical end walls formed with curved parallel front edges, a pair of horizontal runners connecting the opposite ends of the rear edges of said end wall to form a frame, a bed spring secured to said frame, a seat secured to said end walls substantially perpendicular to said spring, and supporting rods slidable radially of the curved edges into positions adapted to prevent rocking of the bed seat about said curved edges when said frame with its spring is in either upright or recumbent position.

2. The structure set forth in claim 1 in combination with means for locking said supporting rods in adjusted positions on said ends.

3. A convertible bed seat comprising a pair of vertical end walls formed with curved parallel front edges, a pair of horizontal runners connecting the opposite ends of the rear edges of said end walls to form a frame, a bed spring secured to said frame, a back cushion secured to said frame in contact with said spring, a cushion seat pivoted to said end walls to swing from a position substantially perpendicular to said spring to another position in supporting contact with said cushion, means for locking said seat in either of said positions, supporting rods slidable on said end walls radially of the curved edges thereof to prevent rocking of the bed seat about said curved edges when said frame with its spring is in either upright or recumbent position, and means for locking said rods in adjusted positions on said walls.

JAMES E. PLEW.
